CLAIM

The ornamental design of a V-bank filter as shown and described.

DESCRIPTION

FIG. 1 illustrates a view of a left side view of a V-bank filter.

FIG. 2 illustrates a front view of the V-bank filter.

FIG. 3 illustrates a right side view of the V-bank filter.

FIG. 4 illustrates a bottom view of the filter.

FIG. 5 illustrates a top view of the V-bank filter.

FIG. 6 illustrates a frontal perspective front view of the V-bank filter where the right side of the V-bank filter has been rotated to be on the top of FIG. 2A.

FIG. 7 illustrates a rear perspective rear view of the V-bank filter where the right side of the V-bank filter has been rotated to be on the top of FIG. 2B.

FIG. 8 illustrates a second frontal perspective front view of the V-bank filter that includes the right side of the V-bank filter.

FIG. 9 illustrates a second perspective rear view of the filter that includes the right side of the V-bank filter; and,

FIG. 10 illustrates a third perspective rear view of the V-bank filter including the left side of the V-bank filter. The broken lines in the figures show portions of the V-bank filter that form no part of the claimed design.
